UNITED STATES PATENT OFFICE.

GEORGE C. BUCH, OF EUREKA, MISSOURI.

BOOT OR SHOE.

SPECIFICATION forming part of Letters Patent No. 281,664, dated July 24, 1883.

Application filed February 7, 1883. (No model.)

To all whom it may concern:

Be it known that I, GEORGE C. BUCH, of Eureka, St. Louis county, Missouri, have made a new and useful Improvement in Boots or Shoes, of which the following is a full, clear, and exact description, reference being had to the annexed drawings, making part of this specification, in which—

Figure 1 is a view in perspective showing 10 (inverted) that part of the boot or shoe with which the improvement is immediately connected; Fig. 2, a view in perspective of the removable portion of the heel; Fig. 3, a view in perspective of the frame used in attaching the 15 heel proper to the boot or shoe; Fig. 4, a view in perspective showing the counter-extension, and Fig. 5 a vertical transverse section through the improved heel.

The same letters of reference denote the same 20 parts.

The present invention relates to that portion of the boot or shoe immediately connected with the heel; and it consists in an improved mode of constructing and attaching the heel.

25 A, Fig. 1, represents a boot or shoe. Only that part of the boot or shoe is shown that is directly associated with the improvement, the remainder of the boot or shoe being of the customary form.

30 B represents the sole.

C represents the counter. In place of terminating the counter at the level of the sole, as hitherto has been the practice, the counter is extended at C' below the level of the sole, and in practice about two-thirds the depth of the heel, and substantially as shown in Figs. 1, 4, and 5. A frame, D, is applied to the outer side of the counter-extension C', the frame being fitted to the extension, and preferably having an inwardly-turned flange, d, which, when the frame is in position, comes against the edge c of the extension C', as seen more distinctly in Fig. 5.

E represents the heel. It is shaped to fit

the space C², inclosed by the counter-extension, extending, also, below the extension, and at its lower end being suitably enlarged to conform to the shape and size of the frame D, substantially as shown in Figs. 1, 2, and 5, the enlargement serving both to strengthen and to give the proper finish to the construction.

By means of suitable fastenings—such as the nails F—the counter and frame are secured to the sole, and by means of other suitable fastenings—such as the screws G—the counter and frame are connected with the heel. This serves to fasten the heel in place; but by removing the screws G the heel can be readily detached, for it is my intention to make the heels E an article of merchandise, manufacturing them 60 of leather, rubber, or other suitable material, and supplying them to the trade ready to be attached to the boot or shoe, and substantially as in the manner described.

The counter-extension C' of itself serves, 65 with the fastenings G, to hold the heel in place; but the frame D is a valuable auxiliary, the frame serving to strengthen the counter-extension and support the heel, and the frame-flange d serving to stiffen and strengthen frame in a 70 lateral direction.

The frame may be of leather, metal, or any material suitable for the purpose, and it may not extend higher than the sole, as shown in Figs. 1, 3, 5; or it may be extended above the 75 sole, as shown at D'.

I claim—

In a boot or shoe, the combination of the heel E, recessed around its upper edge, with the counter-stiffener C, having the downward extension, and the flanged frame D, all secured together and to the boot or shoe by metallic fastenings, substantially as set forth.

G. C. BUCH.
